DESIGN FOR AN ELECTRICALLY-HEATED WAFFLE-IRON.

59,957.

Specification for Design.

Patented Dec. 13, 1921.

Application filed February 11, 1921. Serial No. 444,298. Term of patent 14 years.

To all whom it may concern:

Be it known that I, FRANK F. FORSHEE, a citizen of the United States of America, residing at Flint, in the county of Genesee and State of Michigan, have invented a certain new, original, and ornamental Design for an Electrically-Heated Waffle-Iron, of which the following is a specification, reference being had to the accompanying drawing, forming a part hereof.

The single figure of the drawing is a view, in perspective, of an electrically heated waffle iron, embodying my new design.

I claim:

The ornamental design for an electrically heated waffle iron as shown.

In testimony whereof, I have hereunto subscribed my name this 4th day of Feb., 1921.

FRANK F. FORSHEE.
